U V

UNITED STATES PATENT OFFICE.

JOSEPH HUEBSCH, OF MILWAUKEE, WISCONSIN.

UNIVERSAL IRONING MACHINE.

Application filed February 9, 1924. Serial No. 691,563.

This invention relates to a universal ironing machine.

It has become desirable in laundries to have universal ironing machines in which all kinds of garments or pieces can be ironed or pressed, so that one operative may finish a family washing. This not only tends to prevent loss of garments or articles but provides an equitable distribution of the work where the operatives are paid by piece work.

It is accordingly an object of this invention to provide an ironing machine of a universal character in which the ironing may be done by either a rolling or pressing action, and in which the garments or articles may be advanced a predetermined distance during the pressing operation for advancing an unpressed section to be pressed.

The invention comprises the novel mechanism and combinations hereinafter described and more particularly pointed out and defined in the appended claims.

In the accompanying drawings which illustrate a preferred embodiment of this invention and in which similar reference numerals refer to similar features in the different views:

Figure 1 is a side elevational of the ironing machine.

Figure 2 is an end elevational view of the machine.

Figure 3 is an enlarged sectional view through the machine.

Figure 4 is an enlarged sectional view upon the line 4-4 of Figure 3.

Figure 5 is an enlarged sectional view upon the line 5-5 of Figure 3.

Figure 6 is an enlarged sectional view upon the line 6-6 of Figure 5.

Figure 7 is an enlarged part sectional and part elevational view of the presser member operating mechanism.

In referring to the drawings, there is shown an enclosed casing 1 in which a shaft 2 is suitably journalled that extends beyond the casing for supporting a roller 3 which may be integral with the shaft or secured thereto. The casing 1 is provided with a pair of spaced outwardly directed bearing arms 4 (Figures 2 and 3) in which a shaft 5 is journalled. A pressing member 6 having a lower arcuate surface 7 has a pair of supporting arms 8 secured upon the shaft 5. The arcuate surface 7 of the pressing member corresponds to the curvature of the roller 3 as can readily be seen in Figure 2.

The arms 8 of the pressing member are provided with downwardly inclined weighted arms 9 that normally tend to elevate the pressing member so that a garment or article may be inserted between it and the roller 3.

Mechanism has been provided for yieldingly lowering the pressing member 6, so that no injury will result to an operative if his fingers get caught between the pressing member 6 and roller 3. To this end, a friction clutch member 10 is keyed upon the shaft 5, and is provided with a laterally extending hub upon which a sprocket gear 11 is freely mounted. A hood or housing 12 surrounds the sprocket gear and is attached to the main casing 1, and a coil spring 13 confined upon the shaft 5 between the wall of said hood and the sprocket gear urges the latter into frictional engagement with the friction clutch member 10. A sprocket chain 14 is trained over the sprocket gear 11 and also over a small sprocket gear 15 secured upon an intermediate shaft 16 journalled in suitable bearings in the casing 12. A spur gear 17 is secured upon the shaft 16 and meshes with a spur gear 18 secured upon a shaft 19 journalled in a suitable bearing on the casing 1 and in a bracket 20 extending from the casing. The gear 18 meshes with a gear 21 loosely mounted upon a driven shaft 22 which is journalled in the casing 1. The gear 21 is provided with a jaw clutch adapted to be engaged by a cooperating shiftable jaw clutch member 23. This shiftable jaw clutch member 23 is operatively connected with a lever 24 secured upon a rod 25 which extends through the casing and is provided with an operating handle 25^a. A lever 26 is also secured upon the rod 25 and provided at its upper end with a plunger 26^a having a pointed end 27. This plunger 26^a slidably extends through a slot in the casing 1 for projection in the path of a valve rod 28 having a valve 29 which is adapted for controlling a steam passage in a valve housing 6^a carried by the pressing member 6. A pipe or hose 30 extends from the housing 6^a into the bottom of a diaphragm chamber 31. This rod 28 is also provided with a valve 29^a which controls the exhaust from the pipe 30. A spring 28^a normally closes the valve 29. The diaphragm chamber 31 consists of a lower concave member 31^a pivoted upon a lug 32 on the side of the casing and an upper concave member 31^b which is

secured in sealed relation with the concave section 31^a. The usual diaphragm 32 is supported between the two sections. The concave section 31^b terminates in a hollow bearing tube 33 to which one end of a link 34 is pivoted, the other end of the link being pivotally connected to the counterweight 9. A plunger rod 35 having a disk 36 at its lower end extends from within the concave section 31^b through the tube 33 for actuating the counterweight 9 as will be hereinafter more fully explained.

The aforementioned shaft 22 is provided with a worm wheel 37 which is driven by a worm 38 connected with a suitable source of power. It will therefore be evident that rotation of the worm gear 37 will impart rotation to the shaft 22 and if the clutch 23 is in operative relation with the gear 21, the train of gears 21, 18, 17 and the sprocket gearing will be operated for rotating the shaft 5 for lowering the pressing member 6 and at the same time the plunger 26^a will be extended a sufficient distance to be in the path of the rod 28 as it descends with the presser member 6 to be engaged thereby for opening the steam passage leading to the diaphragm chamber 31. The steam enters the lower concave section 31^a of the diaphragm 30 and exerts enough pressure against the rod 35 for acting upon the weight 9 and forcing the pressing member 6 against the roller 3, the sprocket gearing being effective for rotating the shaft 5 and lowering the pressing member 6 until the friction between the gear 11 and friction clutch 10 is overcome, the fluid pressure applying the final pressure to the pressing member 6.

The ironing roller 3 may be continuously rotated or may be intermittently or fractionally rotated a predetermined extent determined by the arc defined by the pressing member 6. For this purpose a pair of gears 39 and 40 are mounted upon the roller shaft 2, the gear 39 being rigidly secured upon the shaft, while the gear 40 is loose thereon. These gears mesh with pinions 41 and 42 which are loosely mounted upon the driving shaft 22 and are provided with jaw clutches upon their adjacent faces. A clutch member 43 is slidably splined upon the shaft 22 between the pinions 41 and 42. This clutch is adapted to be actuated by a yoke lever 44 secured upon a rod 45. This clutch may be thrown into engagement with the pinion 41 for effecting a continuous drive of the roller shaft 2 or it may be thrown into engagement with the pinion 42 for rotating the roller shaft 2 a predetermined extent as will now be explained.

In referring to Figure 5, it will be observed that a driving pawl 46 is pivoted upon the gear 40. This pawl is adapted for engaging a ratchet wheel 46^a secured upon the shaft 2. A spring 47 connected with the free end

of the pawl 46 and the gear 40 normally tends to withdraw the pawl from engagement with the ratchet wheel. A compression spring 48 extends from the pawl 46 for engaging under an arcuate guard 49 which is slidably mounted upon the rods 50 and 51 for pressing the pawl into engagement with the ratchet wheel.

It will be evident that as long as the end of the spring 48 which is shown as provided with a bevelled head engages under the arcuate guard 49, the pawl will be held in engagement with the ratchet wheel 46^a for rotating the roller shaft 2. However, when the pawl rides out from under the arcuate guard 49, the spring 47 will withdraw the pawl from the ratchet wheel 46^a thereby preventing further rotation of the shaft 2. The guard 49 is connected with the shaft 45 by a link 53. The gear 40 is also provided with a cam 52 extending laterally from one of the spokes thereof. This cam is adapted for engaging against the side of the arcuate guard 49 and shifting it laterally upon the rods 50 and 51 for moving the same out of the path of the pawl 46 and simultaneously rotating the shaft 45 through link 53 for shifting clutch 43 to neutral position for stopping the rotation of gear 40. The design of the arcuate guard 49 should be such as to correspond to the arcuate surface of the pressing member 6 so that the circumferential movement of the ironing roller will equal the arcuate extent of the pressing member 6. The arcuate guard 49 is adapted to be manually shifted by the crank 53 upon the aforementioned shaft 45 which is adapted to be actuated by a handle 54 secured upon the end of the shaft 45 which extends beyond the casing for this purpose. A counterweight 55 secured upon the lower end of a cable 56 is attached thereby to a peg 57 on the gear 40. This cable is suitably guided by a guide 58 attached to the casing. The function of this counterweight is to return the gear 40 after each actuation to its initial starting position with the pawl 46 confined under the lower end of the arcuate guard 49 as shown in Figure 5. A bracket 58^a extends from the casing 1 for supporting an ironing board 59 below the roller 3 upon which a certain amount of hand ironing may be done. A brake band 60 is adjustably secured upon a drum 61 (Figure 6) on the shaft 2. The band may be suitably anchored to the frame. The purpose of this brake is to retard or stop overrunning of the shaft.

The operation of the machine will now be described. Let it be assumed that it is desired to iron articles which require merely a rolling action. The clutch 43 will be connected with the pinion 41 and the handle 25^a will be operated for simultaneously throwing the clutch 23 into engagement with the

gear 21 and swinging the lever 26 for projecting the plunger 26^a into the path of the valve stem 28. If the driving shaft 22 is now rotated from a suitable source of power applied to the worm 38, the shaft 5 will be rotated for lowering the presser member 6, and when the presser member 6 has been sufficiently lowered, the valve stem 28 will engage the plunger or abutment 26^a for opening the valve 29 and admitting steam to the diaphragm for causing the plunger rod 35 to actuate the weight 9 for pressing the member 6 against the roller. The roller shaft will be rotated through the pinion 41 and gear 39, and as the roller rotates it will iron the article in conjunction with the pressing member 6, which will be forced downwardly against the roller by the fluid pressure acting against the plunger rod 35 which engages the counterweight 9 and elevates the same as above explained. When an article has been passed between the roller 3 and the presser member 6, another may be inserted without stopping the machine so that a continuous rolling or ironing action results. Where it is desired to stop the machine, the lever 25^a may be actuated for withdrawing the clutch 23 and the plunger 26^a allowing the spring 28^a to close the steam valve 29 and open valve 29^a for the escape of steam from the diaphragm chamber, the counterweights 9 will then descend for raising the presser member 6 and forcing the plunger rod 35 inwardly and at the same time the link 34 in connection with the diaphragm extension 33 will act as a toggle for swinging the diaphragm chamber outwardly, thereby shifting the plunger rod 35 from engagement with its counterweight 9. Thus, it will be seen that the presser member 6 is automatically raised as soon as the valve 29 is closed against the admission of the steam.

Now, assume it is desired to iron certain classes of garments or articles such as are quite heavy for example, which cannot be readily ironed by a rolling action as just explained. Such articles may be pressed by the before-described machine in the following manner:

Assume that the presser member 6 is in elevated position and the clutch 43 is in inoperative position as shown in Figure 6. The garment or article to be pressed may then be inserted between the roller 3 and the pressing member 6. When the garment has been properly positioned, lever 25^a may be actuated for throwing in the clutch 23 and shifting the lever 26 for projecting the abutment 26^a in the path of the valve stem 28, or the article may be inserted by rotating the roller. If the shaft 22 is now rotated, the presser member 6 will be lowered by the yielding friction drive; the valve 29 will be opened for admitting steam to

the diaphragm for pressing the member 6 against the article, the roller 3 remaining stationary during such operation. When the portion of the garment between the pressing member 6 and the roller has been pressed the pressing shoe may be elevated as before explained. The clutch 43 may then be thrown into engagement with the pinion 42 whereby the gear 40 will be rotated and through the ratchet and pawl connection with the roller shaft 2 the latter will be rotated a distance corresponding to the arcuate surface of the pressing member 6, the pressing member 6 remaining stationary during this operation. When the roller has travelled such an extent, the spring 48 will ride out from under the arcuate guard 49 and permit the spring 47 to release the pawl 46 from engagement with the ratchet wheel. As soon as the pawl 46 is thuswise released, the cam 52 on gear 40 will shift the guard 49 and rotate shaft 45 for automatically throwing out the clutch 43 for disconnecting the pinion 42. The frictional retarder 60 acting upon the roller shaft will immediately stop the same from overrunning. The counterweight 55 will then return the gear wheel 40 to initial starting position. During this predetermined extent of rotation of the roller 3 the garment will have been rotated so as to remove the pressed portion beyond the confines of the presser member 6 and to bring an adjoining unpressed portion into juxtaposition with respect to the presser member 6. The pressing shoe 100 may then be lowered for a second pressing operation. When the second portion has been pressed, the clutch 43 may again be thrown into engagement with pinion 42 for rotating the roller another predetermined distance, as previously explained, for bringing a third portion into position to be pressed as is obvious. The roller, however, may be stopped at any time when pleats or ruffles are encountered by simply throwing the clutch 43 into neutral.

From the foregoing it will be evident that this ironing machine may iron garments by a rolling action, or simply by a pressing action, in which the pressed article may be advanced a predetermined distance. Accordingly any kind of garment or piece of fabric may be ironed in the machine.

I am aware that numerous details of construction may be varied through a wide range without departing from the principles of this invention, and I therefore do not pur-pose limiting the patent granted hereon otherwise than necessitated by the prior art.

I claim:

1. In an ironing machine, the combination with a pressing member, of a roller co-operating therewith, a shaft for supporting said roller, a gear rigidly secured to said

- shaft, a gear loosely mounted upon said shaft, a pawl on said loose gear, a ratchet wheel secured on said shaft for engagement by said pawl, an arcuate guard member in the plane of said ratchet wheel, a yielding abutment between said pawl and guard member, yielding means for retracting the pawl from said ratchet wheel, a cam on said loose gear for coaction with said guard, mechanism including a shiftable clutch for driving either of said gears, and a connection between said guard and clutch.
2. In an ironing machine, the combination with a pressing shoe having an arcuate surface, a roll for coaction with said arcuate surface, a shaft for supporting said roll, a gear fixedly secured upon said shaft, a gear loosely mounted upon said shaft, mechanism for selectively driving one of said gears, and means associated with said loose gear and shaft for rotating said shaft an extent corresponding to the arcuate surface of said pressing shoe.
3. In an ironing machine, a pressing shoe having an arcuate surface, a roll for engagement with said surface, mechanism for continuously rotating said roll, and mechanism for optionally rotating said roll a distance substantially equal to the arcuate surface of said shoe.
4. In an ironing machine, a pressing shoe having an arcuate surface, a roll for engagement with said surface, a shaft for supporting said roll, a gear fixedly secured upon said shaft, means for continuously driving said gear, a gear loosely mounted upon said shaft, and means for establishing a driving connection between said loose gear and shaft adapted for effecting a driving relation for a distance corresponding substantially to the arc defined by said arcuate surface.
5. In an ironing machine, a pressing shoe having an arcuate surface, a roll coacting with said surface, a shaft for supporting said roll, a gear fixedly secured to said shaft, disconnectable means for driving said gear continuously, another driving mechanism for said shaft, and means for rendering said driving mechanism inoperative after said roll has travelled an extent substantially equal to said arcuate surface.
6. In an ironing machine, a pressing shoe having an arcuate surface, a roll coacting with said surface, mechanism for selectively driving said roll continuously, other mechanism for driving said roll and means controlled by said last mentioned mechanism for disconnecting the driving relation between said last mentioned mechanism and roll after partial revolution of said roll.
7. In an ironing machine, the combination with a pressing member, a roll for engaging said member, mechanism for selectively rotating said roll continuously or intermittently, and means operated by a portion of
- said mechanism for limiting the intermittent rotation to a partial revolution.
8. In an ironing machine, a pressing shoe, a roll for cooperating with said shoe, a disconnectable driving mechanism for continuously rotating said roll, and an automatically disconnectable driving mechanism for rotating said roll a partial revolution, said latter mechanism comprising a pair of relatively movable members having a driving relation and means for severing said driving relation after such partial revolution.
9. In an ironing machine, a pressing shoe, a roll for cooperating with said shoe, mechanism for rotating said roll a partial revolution comprising a clutch and a pair of relatively rotatable members having a limited driving relation, and means controlled by the rotation of one of said members for operating said clutch for stopping said roll.
10. In an ironing machine, a pressing shoe, a roll in cooperative relation therewith, a shaft for supporting said roll, a gear fixed on said shaft, a second gear loose on said shaft, a counter shaft, a pair of pinions loosely mounted upon said counter shaft, one in engagement with each gear, a slideable clutch between said pinions, a driving connection between said loose gear and roll shaft for driving said roll a partial revolution, means operated by said loose gear after such partial revolution for shifting said clutch to inoperative position, and means for returning said loose gear to a predetermined position.
11. In an ironing machine, a pressing shoe having an arcuate surface, a roll coacting with said surface, a shaft for supporting said roll, driving mechanism for the shaft comprising a clutch and a pair of members having a driving relation for a partial revolution and means operated by one of said members after such partial revolution for shifting said clutch, and means for returning said last mentioned member to a predetermined position.
12. In an ironing machine, a pressing shoe having an arcuate surface, a roll coacting with said arcuate surface, a shaft for supporting said roll, driving mechanism for rotating said shaft through an arc substantially equal to the arc defined by said arcuate surface, and a means for automatically disconnecting said mechanism from said shaft at the end of said arc of rotation.
13. In an ironing machine, a pressing shoe having an arcuate surface, a roll coacting with said surface, a shaft for supporting said roll, mechanism for continuously rotating said shaft and means for rotating said shaft through an arc substantially equal to the arc defined by said arcuate surface, said means comprising a pair of members, one fast on said shaft and the other loose, a driving connection between said members,

- and means for disconnecting said driving connection automatically at the end of said arc of rotation.
14. In an ironing machine, a pressing member having a pressing surface, a roll for cooperating with said surface, a shaft for supporting said roll, a pair of members, one fast on said shaft and the other loose, means providing a driving connection between said members, means associated with said connection for automatically disconnecting the latter after a partial revolution of said shaft, and means for automatically returning one of said members to a predetermined position.
15. In an ironing machine, a pressing member having an arcuate surface, a roll for cooperating with said surface, mechanism for controlling the rotation of said roll comprising a pair of relatively movable members, and means for automatically severing said movable members after a partial revolution of said roll.
16. In an ironing machine, a pressing member having an arcuate surface, a roll for coaction with said surface, continuous driving mechanism for the roll and intermittent driving mechanism for the roll, means for selectively operating either of said driving mechanisms, said intermittent driving mechanism comprising a pair of members having a driving connection automatically disconnected after a partial revolution and means operated by one of said members for rendering said intermittent driving mechanism inoperative at the end of such partial revolution.
17. In an ironing machine, a pressing member having an arcuate surface, a roll for coacting with said surface, intermittent driving mechanism for said roll for imparting a partial revolution thereto, said driving mechanism comprising a clutch and a pair of members having a limited driving relation automatically disconnectable after a partial revolution, and means operated by one of said members for shifting said clutch to inoperative position.
18. In an ironing machine, a shoe having a pressing surface, a roll coacting with said surface, selectable continuous or intermittent driving mechanism for said roll, and a pair of members associated with said driving mechanism for automatically disconnecting said driving mechanism after a partial revolution of said roll.
19. In a machine of the class described, a roll, a shoe cooperating with said roll, a yieldable friction drive for initially operating said shoe in one direction, fluid pressure means for applying the final pressure to said shoe, and mechanism for simultaneously disconnecting said friction drive and relieving the fluid pressure.
20. In an ironing machine, a roll, a shoe cooperating with said roll, a yieldable drive for operating said shoe, a fluid pressure system for applying the final pressure to the shoe, driving mechanism having a clutch connection with said yieldable drive, and mechanism for simultaneously operating said clutch connection and controlling said fluid pressure system.
21. In an ironing machine for pressing or rolling action, a pressing member having an arcuate surface, a roll adapted for coaction with said surface, mechanism for selectively continuously or intermittently rotating said roll, said mechanism including a pair of members having means associated therewith to effect an automatic disconnection after said roll has rotated an extent substantially equal to said arcuate surface.
22. In an ironing machine for pressing or rolling action, a pressing member having an arcuate surface, a roll for coaction with said surface, driving mechanism for selectively continuously or intermittently rotating said roll, said mechanism including a pair of members having a limited driving rotation, and means actuated by one of said members for disconnecting said driving mechanism.

In testimony whereof I have hereunto
subscribed my name.
JOSEPH HUEBSCH.
